UNITED STATES PATENT OFFICE

2,620,494

ABSORBENT PROTECTIVE PAD

Leah A. Kay, Amarillo, Tex.

Application November 5, 1947, Serial No. 784,183

7 Claims. (Cl. 5—354)

1. This invention relates to new and useful improvements in absorbent protective articles.

It is a more or less common practice, in the care of infants or invalids, to use a sheet of rubber or other water-impervious material and a protective absorbent pad, such as a blanket, toweling, or quilted absorbent material, to protect the bed or the clothing of the user from moisture. The use of separate sheets of rubber and absorbent material makes handling of the materials difficult and unwieldy, and once the pad of absorbent material has become moist or used, it must be washed and sterilized or thrown away and a new pad provided. Furthermore, if the pad is used on a bed under the infant or invalid for protecting the bedding, the pad and the rubber sheet both become wrinkled or displaced in many cases, and frequently the two elements become entirely separated so as to defeat the purpose for which they are used.

It is, therefore, one object of this invention to provide an improved unitary absorbent protective article particularly adapted for use for the protection of bedding, or the protection of the clothing of the user when handling infants and invalids and the like.

An important object of the invention is to provide an article of the character described, wherein a non-absorbent foraminous or mesh woven envelope encloses a sheet of rubber or other water-impervious material and a pad of absorbent material, whereby moisture may pass through the non-absorbent foraminous or mesh envelope to the absorbent pad and be absorbed therein and the moisture-impervious material will prevent the moisture from passing from the absorbent pad to the bedding or clothing.

Another object of the invention is to provide an article of the character described which is provided with integral means for securing the article in a substantially stationary position on a bed or to the person of the wearer.

A further object of the invention is to provide an improved absorbent protective article of the character described wherein the non-absorbent foraminous or mesh material envelope encloses and supports a sheet of moisture-proof or moisture-impervious material, such as rubber, and a body of disposable absorbent material, whereby when the absorbent material has served its purpose it may be removed from the envelope and completely disposed of and the envelope of non-absorbent foraminous or mesh material and the rubber sheet may be sponged or rinsed off and wiped dry and a dry absorbent

pad inserted in the envelope, whereupon the article is again ready for use.

Still another object of the invention is to provide, in an absorbent protective article of the character described, an absorbent pad of disposable absorbent material, such as paper toweling or the like, this eliminating the necessity of washing and drying the article after its use.

Additional objects and advantages of the invention will be readily apparent from the reading of the following description of a device constructed in accordance with the invention, and reference to the accompanying drawings thereof, wherein:

Figure 1 is a plan view of an absorbent protective article constructed in accordance with the invention,

Figure 2 is a longitudinal, vertical sectional view of the article, taken on the line 2—2 of Figure 1,

Figure 3 is an enlarged, fragmentary, sectional view, taken on the line 3—3 of Figure 1, and showing the open end of the envelope, and

Figure 4 is a view in elevation of a protective article constructed in accordance with the invention and provided with shoulder straps whereby it may be worn as an apron.

In the drawings, the numeral 10 designates a substantially rectangular envelope made of mesh nylon or other foraminous non-absorbent material, said envelope including an upper outer sheet 11 and a lower outer sheet 12 of the foraminous or mesh material sewn together along three marginal edges as indicated at 13, whereby the envelope forms a receptacle having an open end 14. The edges of the upper and lower outer sheets are turned under and separately hemmed at the opening 14 to strengthen the same. It is preferable that loops 15 of cloth tape material be sewn between the two sheets of foraminous mesh material at equally spaced points on opposite sides of the envelope, as clearly shown in Figures 1 and 2, whereby the envelope may be secured in a relatively stationary position on a bed or other object, or may be secured to the person of the user, for a purpose which will be hereinafter described.

A flat rectangular sheet 17 of rubber or other water-impervious material, slightly smaller in size than the envelope, is inserted through the open end 14 of the envelope between the lower and upper sheets. A pad 18 of absorbent material, such as toweling, or a quilted absorbent sheet, or a disposable absorbent material such as paper toweling, paper diaper material, or the

like, is inserted into the open end 14 of the envelope between the upper outer sheet of mesh material 11 and the moisture-impervious or rubber sheet 17, as clearly shown in Figure 2. Manifestly, the absorbent material may be positioned between the rubber sheet and either the upper or lower outer sheets of mesh material, or between the rubber sheet and both the upper and lower outer sheets of mesh material, so that either side of the article may be used as an absorbent and protective means.

In use, the envelope 10, having the rubber sheet 17 and absorbent material 18 positioned therein, is placed on the bed, or is secured to the body of the wearer, with the rubber sheet on the inner side and the absorbent material on the outer side. Then, if water or other fluid falls on the envelope it will pass through the non-absorbent mesh material of the envelope and be absorbed by the absorbent material 18. The rubber sheet 17 prevents the moisture from passing through the pad of absorbent material to the bed therebelow, or to the clothing of the wearer.

When the absorbent material has become moistened in use, it may be removed from the envelope 10 and washed and sterilized, if the absorbent material is toweling or other reusable material, or, the absorbent material may be thrown away if it is a disposable sort of material such as paper toweling or the like.

The non-absorbent nylon envelope and the rubber sheet 17 may then be sponged off with a damp cloth to clean them, and a fresh absorbent pad inserted through the open end 14 of the envelope between the rubber sheet 17 and the upper outer sheet of mesh material 11 of the envelope, whereupon the article is again ready for use.

Manifestly, it is not necessary to thoroughly wash the envelope 10 and wait for it to dry, since the foraminous or mesh material of which the envelope is made is a non-absorbent material, such as nylon or the like, which does not absorb water and may be sponged and wiped dry with a cloth or shaken dry so as to be ready for immediate use. Thus, a disposable absorbent material, such as paper toweling or the like, may be used in the envelope to absorb moisture, and may be disposed of after use and becoming dampened, while the envelope and rubber sheet need only be sponged or rinsed clean and shaken or wiped dry to be again ready for use.

If desired, the lower sheet of the envelope may be formed of a sheet or rubber or other moisture-impervious material, and the upper sheet of non-absorbent or moisture-impervious foraminous or mesh material may be secured to such moisture-impervious imperforate lower sheet to form the envelope, and the absorbent material may then simply be inserted in the envelope between the rubber inner sheet of the envelope and the foraminous or mesh upper sheet thereof. Otherwise, the use of this form of the article is the same as that already described, except that the envelope is not reversible. The imperforate inner sheet may be of plastic or other pliable moisture-impervious material, if desired, and the foraminous outer sheet may also be of plastic or other pliable moisture-impervious material.

Obviously, the imperforate moisture-impervious sheet may be sewn or otherwise secured at its marginal edges between the two outer foraminous sheets of the envelope 10 so as to be non-removable. Such a construction provides two separate pockets for receiving absorbent material,

one pocket on each side of the imperforate moisture-impervious sheet between said sheet and each of the outer sheets of foraminous material, whereby the protective article is reversible and absorbent material may be inserted into either or both of the pockets, as desired. This arrangement prevents separation of the envelope and the rubber sheet and thus lessens the chance of loss of either element. Furthermore, the imperforate moisture-impervious sheet, when so secured or sewn in place in the envelope, reduces the wrinkling and deformation of the envelope when the same is rinsed or sponged clean and wiped or shaken dry.

The envelope may take any desired size and shape, and may have any desired means for securing or attaching it to the bed or to the person of the user.

The loops of tape material 15 may be of cloth or any other suitable washable material and are provided for tying the envelope in place on the bed, whereby the infant or invalid under whom it is used will not be able to readily displace or wrinkle the same to impair its effectiveness. The loops may also be used to receive a belt strap (not shown) by means of which the envelope may be secured to the waist of the user holding an infant in his lap, whereby the envelope is maintained in place for use.

In Figure 4, the envelope is shown as having elongate shoulder straps 20 sewn or otherwise attached to it at its two upper corners, and short tie strings 21 sewn or otherwise attached to it intermediate its ends and adapted to be tied to the shoulder straps 20 to secure the envelope 10 in position on the person of the user. Manifestly, while the envelope is shown as rectangular in shape, it may be of any other desired configuration. Also, means other than the straps may be employed for securing the article to the person of the user.

From the foregoing, it will be seen that an absorbent protective article has been provided which includes an envelope made of mesh nylon or other foraminous non-absorbent material, which is open at one end and which encloses a sheet of water-impervious material, such as rubber or the like, and a pad or mass of absorbent material, such as toweling, or disposable absorbent filler material, which may be removed from the envelope and washed or thrown away when used and dampened. It is readily apparent that the non-absorbent foraminous or mesh material of the envelope permits moisture to pass through the foraminous material to the absorbent pad into which it is absorbed, and that the rubber sheet prevents passage of the moisture from the pad to the bedding or clothing of the wearer or user.

It will further be seen that the non-absorbent foraminous or mesh material of the envelope permits the envelope to be rinsed or sponged clean and shaken or wiped dry, whereupon it is again ready for immediate use upon replacement of the absorbent pad, thus eliminating the washing and long period of drying which would otherwise be necessary. Furthermore, since the two sheets forming the envelope are each preferably of non-absorbent or moisture-impervious foraminous or mesh material, it is readily apparent that the article is reversible, and that masses of absorbent material may be inserted between the rubber sheet in the envelope and each sheet of mesh material, whereby either side of the article may be used as a protective

and absorbent means. Also, the imperforate moisture-impervious sheet may be sewn or otherwise positively secured at its marginal edges between the two sheets of foraminous material, so as to be positively held in place in the envelope.

It will further be noted that the article may take any desired shape and may be fastened to the bedding or the person of the wearer in any desired suitable manner.

The foregoing description of the invention is explanatory only, and changes in the details of the construction illustrated may be made by those skilled in the art, within the scope of the appended claims, without departing from the spirit of the invention.

What I claim and desire to secure by Letters Patent is:

1. An absorbent protective article including, a pair of coextensive marginally contiguous sheets of water-impervious foraminous material fixedly joined together along a major part of their contiguous coextensive marginal edges and having an entrant opening formed by the unjoined marginal portion, a sheet of imperforate moisture-impervious material removably disposed between the two sheets of foraminous material, and a separately removable mass of absorbent material between one sheet of foraminous material and the moisture-impervious sheet.

2. An absorbent protective article of the character set forth in claim 1 wherein, the sheet of foraminous material adjacent the mass of absorbent material is nylon mesh material.

3. An absorbent protective article of the character set forth in claim 1 wherein, the mass of absorbent material is disposable non-reusable material.

4. An absorbent protective article including, an envelope formed of two sheets of material fixedly joined along their marginal edges and having an opening along one edge, at least one sheet of the envelope being formed of moisture-impervious foraminous material, the other of said sheets being formed of an imperforate moisture-impervious material, and a mass of absorbent material removably disposed within the envelope.

5. An absorbent protective article including, an envelope formed of two sheets of nylon mesh material fixedly joined together along their marginal edges and having an unjoined marginal opening, a sheet of rubber removably disposed within the envelope and substantially coextensive therewith, and a separately removable mass of disposable absorbent material between the rubber sheet and one sheet of mesh material.

10 6. An absorbent protective article of the character set forth in claim 5 wherein, a second mass of separately removable absorbent material is disposed between the rubber sheet and the other sheet of mesh material.

15 7. An envelope, for an absorbent protective article, formed of two sheets of moisture-impervious foraminous material fixedly joined together along their marginal edges and having an unjoined marginal opening, and an imperforate moisture-impervious sheet coextensive with and disposed between said foraminous sheets, said imperforate sheet being fixedly secured along its marginal edges to the fixedly joined edges of said foraminous sheets to form 20 two separate pockets in the envelope each communicating with the unjoined marginal opening of said envelope, said imperforate sheet being held against wrinkling or displacement from its position in the envelope.
